CLAIM

The ornamental design for a storage and carrying case for a fire extinguisher canister, as shown and described.

DESCRIPTION

FIG. 1 is a perspective view of a first embodiment of a storage and carrying case for a fire extinguisher canister in a closed position.

FIG. 2 is bottom view of the case of FIG. 1.

FIG. 3 is a top view thereof;

FIG. 4 is an end view thereof, the opposite end view being identical thereto;

FIG. 5 is a front side view thereof;

FIG. 6 is a back side view thereof;

FIG. 7 is a perspective view of a first embodiment of a storage and carrying case for a fire extinguisher canister in an open position;

FIG. 8 is a top view of the case of FIG. 7;

FIG. 9 is a bottom view thereof;

FIG. 10 is an end view thereof, the opposite end view being identical thereto;

FIG. 11 is a front side view thereof;

FIG. 12 is a back side view thereof;

FIG. 13 is a perspective view of a second embodiment of a storage and carrying case for a fire extinguisher canister in a closed position;

FIG. 14 is a bottom view of the case of FIG. 13;

FIG. 15 is a top view thereof;

FIG. 16 is a handle end view thereof;

FIG. 17 is a second end view thereof;

FIG. 18 is a front side view thereof;

FIG. 19 is a back side view thereof;

FIG. 20 is a perspective view of a second embodiment of a storage and carrying case for a fire extinguisher canister in an open position;

FIG. 21 is a top view of the case of FIG. 20;

FIG. 22 is a bottom view thereof;

FIG. 23 is a handle end view thereof;

FIG. 24 is a second end view thereof;

FIG. 25 is a front side view thereof; and,

FIG. 26 is a back side view thereof.

The broken lines illustrate portions of the storage and carrying case for a fire extinguisher canister and form no part of the claimed design.
